UNITED STATES PATENT OFFICE.

JACOB APOLL, OF HAMMOND, INDIANA.

FASTENER.

1,106,534.

Specification of Letters Patent. Patented Aug. 11, 1914.

Application filed March 31, 1913. Serial No. 757,743.

To all whom it may concern:

Be it known that I, JACOB APOLL, a citizen of the United States, and a resident of Hammond, in the county of Lake and State of Indiana, have invented certain new and useful Improvements in Fasteners; and I do hereby declare that the following is a full, clear, and exact description thereof, reference being had to the accompanying drawings, and to the letters of reference marked thereon, which form a part of this specification.

This invention relates to means for permanently and rigidly joining or uniting two wooden members which meet at their edges with the edge of one member in abutting relation to the other member, such, for instance, as the two walls of a box or the like at a corner of the same.

The invention has for one of its objects to provide a metal fastener of such construction that the same may be readily and quickly applied to the two wooden members to be joined, and in addition to its function of providing a rigid connection between such members, to stiffen and strengthen the said members at the joint or corner formed by the united margins of the same.

In its general features, my invention employs a metal strip provided with two sets of prongs, the body portion of said strip being adapted for insertion into a groove formed longitudinally in the end margin of one wall of a box or the like, and the prongs being so disposed that one set of the same have their end portions driven into the wall into which the body portion is inserted, to effect the rigid attachment of the strip to said wall, and the other set may be driven transversely through the other wall, to effect the joining of said walls.

This invention consists in the matters hereinafter described and more particularly pointed out in the appended claims.

In the accompanying drawings illustrating my invention: Figure 1 is a perspective view of a wooden or like box showing metal fasteners, connecting the side and end walls at the corners of the box, constructed in accordance with my invention; Fig. 2 is a perspective, fragmentary view of a part of one of said metal fasteners; Fig. 3 is a plan view of a flat blank from which the metal fastener is made; Fig. 4 is an enlarged fragmentary sectional view of one wall of the box showing said metal fastener applied to

the lateral edge or margin thereof; the dotted lines indicating the position occupied by one set of the prongs of said fastener before being driven into engagement with said wall; Fig. 5 is an enlarged fragmentary sectional view taken on a plane indicated by line 5—5 of Fig. 1; and Fig. 6 is a perspective fragmentary view of the side and end walls at one corner of the box, showing the metal fastener applied to the end wall and the side wall in position just prior to the time that the same is driven into engagement with one set of the prongs of said fastener.

Referring to the drawings, illustrating in detail one of the preferred forms of my invention, the same is shown as applied to a wooden box 10 for uniting or joining the side walls 11, 11 with the end walls 12, 12 at the corners of the box. Said box 10 is provided with a bottom wall 13 secured to the associated edges of the side and end walls in any suitable manner, but preferably by nails (not shown).

The metal fastener forming the subject-matter of the present invention is preferably cut or stamped from a flat piece of sheet metal. Said fastener comprises a body-member 14, in the form of a narrow elongated plate or strip, and on one of the longitudinal edges of said body-member 14 is provided two sets of longitudinally spaced integral prongs, 15 indicating the prongs of one set and 16 indicating the prongs of the other set. As shown in the drawings, the prongs 15 of one set are all of the same length and are spaced at equal distances apart. Said prongs 15 are in the plane of said body-member and are arranged at right angles to the longitudinal edge of said body-member 14, from which they extend. Said prongs 15 are also provided with pointed ends. The prongs 15 will hereinafter be referred to as the straight prongs.

The prongs 16 of the other set extend from the same edge of said body-member 14 as the straight prongs 15 and are arranged severally between or in alternation with the said straight prongs 15, and are also spaced longitudinally at equal distance apart. Said prongs 16 will preferably be made of greater length than the length of the straight prongs 15, combined with the width of the body-member or strip 14. Said prongs 16 are also pointed at their ends. Each prong 16 is bent, laterally of the body member, from

the position it occupies in the flat blank, as shown in said Fig. 3, so as to form an abrupt bend at its base or point of connection with the margin of said body-member 14, and in such manner that the base portion 16^a of said prong extends or projects at substantially a right angle to the side face of said body-member. The said prong 16 is again bent at a point at a distance from its base, so as to form a straight part 16^b, and its point or end is again bent to form a straight terminal part 16^c. When so bent, the several parts of the prong lie in a plane at right angles to the body-member, as clearly shown in Fig. 2. The prongs 16 will be herein-after referred to as the bent prongs.

A joint for the corner of a box or the like, made by the use of a metal fastener of the character described, is constructed as follows: In the edge or marginal surface 17 of the end wall 12, is formed a groove 18, extending inwardly from said surface with its side walls parallel with the side faces of said end wall. Usually such groove 18 will extend the entire length of such edge 17 of the end wall 12. The groove 18 is of a depth equal to the width of the body-member 14 of the fastener. Said body-member or strip 14 is inserted or seated in said groove 18 with its longitudinal edge opposite to that on which the prongs 15 and 16 are formed, at the bottom of said groove. By reason of the fact that the depth of the groove 18 is equal to the width of said body-member 14, as hereinbefore stated, the longitudinal edge of said body-member 14 to which said straight and bent prongs 15 and 16 are connected, will be approximately flush with the grooved edge 17 of said end wall 12. Said body-member 14 will usually extend the full length of said groove 18. When the body-member 14 is located in said groove 18, the straight prongs 15 project outwardly from and substantially at right angles to the grooved edge 17 of said end wall. The base section 16^a of each bent prong 16 is made equal in length to the space between the groove 18 and the inner face of the end wall 12, so that said base section 16^a will rest against the surface of the edge 17 of said end wall 12, while the intermediate sections 16^b and pointed sections 16^c extend over or overlap the inner face of said end wall, and will extend inwardly from said grooved edge 17 with their points out of contact with the inner face of said end wall. The position occupied by the bent prongs 16 at this time is shown in dotted lines in Fig. 4; the pointed ends of the bent prongs 16 being spaced from the body-member 14 a sufficient distance to permit said pointed ends to pass over the said inner face of the wall when the body-member 14 is inserted into said groove 18. The end portions 16^c of the bent prongs 16 are

now forced toward the end wall so as to bend the intermediate sections 16^b inwardly and to drive the pointed ends of the terminal portions 16^c into said end wall, while bringing said intermediate sections 16^b against the inner face of the same. By reason of the length of said bent prongs 16, as hereinbefore mentioned, the pointed end portions 16^c thereof enter the end wall at a distance rearwardly of the body-member 14, as shown in full lines in said Fig. 4 and in Fig. 5. The side wall 11 of the box is now placed in proper position against the pointed ends of the straight prongs 15, and the latter are driven through the said side wall 11 by forcing said side wall 11 toward and into contact with the grooved edge 17 of said end wall 12. Owing to the fact that said straight prongs 15 are longer than the thickness of said side wall 11, the pointed ends of said straight prongs 15 project slightly beyond the exterior face of said side wall 11, and are finally bent back or clenched against said side wall. The base sections 16^a of the prongs 16 become, when the side wall 11 is driven into contact with the end wall 12, embedded in said side wall, as shown in Fig. 5.

While I have shown and described but one form of my metal fastener, it is to be understood the same may be variously modified in its details of construction without departing from the spirit of my invention, and I do not, therefore, desire to be limited to the construction illustrated only in so far as it is pointed out in the appended claims.

I claim as my invention:—

1. In combination with two wooden members, a metal fastener for uniting said members, comprising a body member provided with two sets of prongs; the prongs of one set being inserted in one of said wooden members while the prongs of the other set engage the other of said wooden members and have their end portions inserted into said last mentioned wooden member with such end portions disposed transversely with relation to, and directed toward, the plane of said body member, for securing said body member to the last mentioned wooden member.

2. In combination with two wooden members, one of which is provided with a marginal groove, a metal fastener for uniting said members comprising a body-member located in said groove and provided with two sets of prongs; the prongs of one set having their ends bent and inserted into the grooved member in a direction toward said body-member to hold the latter in engagement with said grooved member, and the prongs of the other set being inserted into the other of said wooden members.

3. In combination with two wooden mem-

- bers, one of which is provided with a marginal groove, a metal fastener comprising a body-member seated in said groove, said body member being provided with two sets 5 of prongs, one set of which are bent and driven into and at the rear of the edge of said grooved member, and the other set of said prongs being inserted into the other of said wooden members.
- 10 4. In combination with two wooden members, one of which is provided with a marginal groove, a metal fastener comprising a body-member seated in said groove, said body member being provided with two sets 15 of prongs, one set of which are bent backwardly and driven into the grooved member and the other set extending through and having their pointed ends clenched against the other member.
- 20 5. A metal fastener comprising a flat elongated body-member provided on one of its side edges with two sets of laterally extending prongs arranged with the prongs of one set in alternation with the prongs of 25 the other set; the prongs of one set being in

the plane of the body member and substantially straight, and the prongs of the other set being bent in planes perpendicular to the body member with their ends directed toward the plane of said body-member. 30

6. A metal fastener, comprising a flat elongated body-member provided on one of its side edges with two sets of laterally extending prongs, the prongs of one set being longer than the prongs of the other set and 35 arranged with the prongs of one set in alternation with the prongs of said other set; the prongs of one set being in the same plane with each other and substantially straight, and the prongs of the other set 40 being bent in planes perpendicular to said body-member.

In testimony, that I claim the foregoing as my invention I affix my signature in the presence of two witnesses.

JACOB APOLL.
